[57] CLAIM

The ornamental design for a file drawer, as shown and described.

DESCRIPTION

FIG. 1 is a perspective view of a file drawer showing my new design;

FIG. 2 is a right side elevational view thereof, the environmental structure shown in broken lines being for illustrative purposes only;

FIG. 3 is a right side elevational view similar to FIG. 2 showing the file drawer partly open;

FIG. 4 is a front elevational view of FIG. 1;

FIG. 5 is a rear elevational view thereof;

FIG. 6 is a bottom plan view thereof;

FIG. 7 is a top plan view thereof; and

FIG. 8 is a perspective view which differs only in that the top surface is continuous and flat.
